UNITED STATES PATENT OFFICE.

ADALBERT W. FISCHER, OF PHILADELPHIA, PENNSYLVANIA, ASSIGNEE TO SCHUTTE AND KOERTING COMPANY, OF PHILADELPHIA, PENNSYLVANIA, A CORPORATION OF PENNSYLVANIA.

JET APPARATUS.

1,151,259.

Specification of Letters Patent. Patented Aug. 24, 1915.

Application filed June 29, 1911. Serial No. 636,002.

To all whom it may concern:

Be it known that I, ADALBERT W. FISCHER, a subject of the Emperor of Germany, residing in the city and county of Philadelphia, in the State of Pennsylvania, have invented a certain new and useful Improvement in Jet Apparatus, of which the following is a true and exact description, reference being had to the accompanying drawings, 10 which form a part thereof.

My present invention relates to jet apparatus and has for its main object the provision of a simple and effective jet device having a plurality of jet orifices formed and 15 disposed that the fluid passing through these orifices at high velocity issues therefrom in the form of a plurality of separate thin flat streams. My improvement, while not limited to such use, is particularly valuable for 20 use in apparatus employed for exhausting air or other gas from a chamber or space by the action of jets of air, steam or water discharged into a conduit leading away from said chamber or space.

25 The various features of novelty which characterize my invention are pointed out with particularity in the claims annexed to and forming a part of this specification.

For a better understanding of the invention, however, and the purposes accomplished and advantages obtained by its use, reference should be had to the accompanying drawings and descriptive matter in which I have illustrated and described a preferred form of apparatus embodying my invention.

Of the drawings, Figure 1 is a partial sectional elevation of an exhaust apparatus in which my invention is utilized. Fig. 2 is a 40 sectional elevation of the jet nozzle head employed in Fig. 1, the section being taken on the line 2-2 of Fig. 3. Fig. 3 is an inverted plan of the jet nozzle head. Fig. 4 is a plan view of the jet nozzle proper. Fig. 45 5 is an enlarged partial section taken on the line 5-5 of Fig. 2, and, Fig. 6 is a section taken on the line 6-6 of Fig. 5.

In the apparatus shown in Fig. 1, E, represents a conduit forming the mixing chamber and discharge pipe of an exhausting apparatus. As shown, said conduit is closed at one end by a head E' through which extends the jet supply pipe D delivering the impelling fluid, usually water, but which

may be air, steam, or other fluid under pressure, to the jet nozzle A, from which it is discharged in axial jets or streams at high velocity. E² represents a branch pipe opening to the conduit from the chamber or space to be exhausted, and of which the conduit E forms in effect a continuation. The conduit E proper, is advantageously constricted in front of the nozzle A as indicated at E'. In so far as above described the apparatus disclosed does not differ essentially 55 from the apparatus heretofore known, but the apparatus disclosed does differ from that heretofore known, however, in the character of the jet nozzle head A.

As shown, the jet nozzle head A comprises a cup-shaped body having a central discharge orifice A⁴ adapted to be threaded on to the end of the jet supply pipe D. At its base this body member is formed with a seat A² for the jet orifice member B. The member B as shown is in the shape of a flat disk and is secured in place by the ring nut C in threaded engagement with the flange-like portion A' of the nozzle head. Lugs C' are formed on the underside of the nut C by means of which the latter may be screwed into and out of place. The orifice member B is formed with a plurality of similar orifices B' which are of such a character that the jets issuing from them are thin and flat, as indicated at X', in Figs. 5 and 6. As illustrated, each jet orifice B' is formed by transverse narrow grooves or slots B² and B³, which are formed in the opposite sides of member B and intersecting at their bottoms 80 at B⁴. With a jet orifice of the character described the shape of the discharge end portion of the orifice formed by the slot B², and also the direction of flow of the central orifice portion B⁴, given the fluid passing through the orifice by the walls of the slot B³ contribute to the production of the ribbon-like jet described and illustrated. A practical advantage of forming the orifice in this manner is that the slots B² and B³ 85 may be readily formed by a milling cutter or other rotating metal cutting tool. A jet orifice member having a single orifice formed in it as described, while novel with me, is not claimed herein, as it forms the subject matter 90 of my prior copending application, Serial No. 602,160, filed January 12, 1911.

The jet orifices should be so arranged that

the jets do not intersect each other in immediate proximity to the jet orifice member B. To accomplish this in the apparatus disclosed herein, the discharge orifices B' in the disk B are arranged in concentric circular rows with the discharge portions B² of the orifices tangential, or practically so, to these rows, and the orifices in adjacent rows do not lie along the same radial lines.

10. The apparatus described is particularly advantageous when the spray nozzle is employed in exhaust apparatus of the general type shown in the drawings. In such apparatus the extent to which the jet or impelling fluid acts upon and sets in motion the fluid in the conduit or chamber into which the jet discharges is to a large extent a function of the extent of surface of the jet streams and is due to the friction, so to speak, between the skin of the jet streams and the surrounding fluid. The apparatus disclosed obviously on account of the thin ribbon-like form of the jets presents a large jet stream area in proportion to the cross sectional area of these jet streams, and the division of the jet flow into a plurality of separate spaced apart streams permits the fluid operated upon to flow freely around and into contact with the various jets so that bubbles or globules of the fluid acted upon are enmeshed so to speak in the jet material and have the desired velocity imparted to them.

While in accordance with the provisions of the statutes I have illustrated and described the best form of my invention now known to me, it will be apparent to those skilled in the art that changes may be made in the form of the apparatus disclosed without departing from the spirit of my invention, and that under some conditions, it may be advantageous to use certain features of the invention without a corresponding use of other features.

Having now described my invention, what

I claim as new and desire to secure by Letters Patent, is:

1. A jet nozzle member having a plurality of spaced apart discharge orifices formed in it which terminate at the discharge surface of said member in narrow elongated slots and comprise also narrow elongated slots leading away from the inlet surface of said member and each extending transversely to and intersecting the slot in which the outer end of the corresponding orifice terminates.

2. A jet nozzle comprising a chambered body portion a disk forming a portion of the wall of the chamber in said body portion and means for detachably securing said disk in place, said disk having formed in it a plurality of spaced apart jet orifices arranged in concentric circular rows and each comprising an outlet end portion in the form of a narrow elongated slot and an inlet end portion of the form of a narrow elongated slot transverse to said outlet end portion and intersecting the latter.

3. A nozzle comprising a chambered body portion, a disk forming a portion of the wall of the chamber in said body portion and means for detachably securing the disk in place, said disk having formed in it a plurality of jet orifices arranged in concentric circular rows and each comprising an outlet portion in the form of a narrow elongated slot opening from the discharge side of said disk and a narrow elongated slot opening from the inlet side of the disk and extending transversely to the first mentioned elongated slot and intersecting the latter, the inlet portions of the various orifices being substantially radial to the center of said disk.

ADALBERT W. FISCHER.
